UNITED STATES PATENT OFFICE.

JOHN G. PATTON AND ALBERT D. FENWICK, OF PHILADELPHIA, PENNSYLVANIA, AS
SIGNORS, BY DIRECT AND MESNE ASSIGNMENTS, TO MAZIE K. PATTON, OF PHILA-
DELPHIA, PENNSYLVANIA.

CANDY PACKAGE.

Application filed June 10, 1922. Serial No. 567,347.

To all whom it may concern:

Be it known that we, JOHN G. PATTON, a citizen of the United States, residing at Philadelphia, county of Philadelphia, State 5
of Pennsylvania, and ALBERT D. FENWICK, a citizen of the United States, residing at Philadelphia, county of Philadelphia, State 10
of Pennsylvania, have invented a new and useful Candy Package, of which the following is a specification.

Our present invention comprehends a novel construction of a package or container which has been especially designed for the packing of candy under a vacuum.

15 In the packaging of candy such as, for example, fudge, it has not been practicable up to the present time to pack it in such a way that it will not deteriorate.

20 Fudge contains a considerable amount of moisture when it is first manufactured and after a few weeks it dries out and is not a salable product. In attempting to pack candy in a can or tin under the vacuum process, it has been found that if the sun 25 shines on the can or tin the fudge which is in close proximity to the wall of the tin becomes affected and the same holds true if the can is left in close proximity to any source of heat.

30 In accordance with our present invention, the fudge is packed within the can in such a manner that there is an insulating space entirely around the candy.

35 Other novel features of construction and advantage will hereinafter more fully appear in the detailed description and the appended claims.

40 For the purpose of illustrating our invention, we have shown in the accompanying drawing a typical embodiment thereof which is at present preferred by us, since this embodiment will be found in practice to give satisfactory and reliable results. It is, however, to be understood that the various instrumentalities of which our invention 45 consists can be variously arranged and organized and that our invention is not limited to the precise arrangement and organization of these instrumentalities as 50 herein shown and described.

Figure 1 represents, in perspective, a candy package embodying our invention, with one end removed for the sake of clearness of illustration.

Figure 2 represents a section on line 2—2 55 of Figure 1.

Figure 3 represents a section on line 3—3 of Figure 2.

Figure 4 represents, in perspective and in detached position, an end spacing member 60 employed. Figure 5 represents a top plan view of a section of an article container.

Figure 6 represents a top plan view of another form of section of article container 65 which may be employed.

Similar numerals of reference indicate corresponding parts.

Referring to the drawing,

1 designates a can or container which 70 may have any desired contour but which, as illustrated, is cylindrical and has the ends 2 which are crimped to the juxtaposed body portions of the can. In practice, one end of the can is secured in sealed position to the body portion of the can and after the 75 material to be packed has been placed within the can, the other end is secured in position within a vacuum chamber so that the goods will be packed under a vacuum. Goods as heretofore packed under the 80 vacuum process have simply been placed within a single walled can and the open ends sealed and closed while a vacuum is being applied to the interior of the can. In these prior methods many articles such as, 85 for example, fudge, if packed in this way, could not be kept in a satisfactory condition. In the bottom of the can we place an end spacing member 3 preferably formed of metal and having opposite sides deflected, as at 4, in order to space the body portion 90 from the juxtaposed end wall of the can.

In order to stiffen the body portion cuts 95 are made in it and the tongues 5 are bent outwardly so as to have the same function as the deflected sides or flanges 4. The body portion of an end spacing member is provided with a multiplicity of perforations 6. The end member 7 at the opposite end which serves as a spacing member, see Figure 2, 100 is constructed in a similar manner so that the detailed explanation of one will suffice for both. 8 designates the inner container for the material which is to be packed which has, as illustrated, a polygonal contour and 105 which can be formed from one or more sheets of sheet material which preferably would be metal.

We have shown a rectangular shaped inner container 8 in which the metal at the corners is deflected upon itself to form the spacing projections 9 and at the free ends 5 of the sheet the material is deflected outwardly to form the spacing projection 10, see Figure 3. The side walls are perforated, as indicated at 11. In this manner air chambers 12 are formed around the side 10 walls of the inner container, an air chamber 13 being formed at the bottom, and an air chamber 14 at the top, so that the material packed is surrounded on all sides by air which serves as an insulating medium.

15 designates the box of fudge which it is desired to pack in such a manner that it will not deteriorate. In carrying out our invention, the bottom end spacing member 3 is spaced within the can and the fudge is 20 placed within the inner container 8. The inner container 8 is then placed within the can 1 and the top spacing member 7 applied. The top of the can is then secured in sealed condition with respect to the body 25 portion of the can within a vacuum so that a vacuum is present between the inner and outer walls of the package. It will be seen that in this manner if the can is placed in close proximity to a source of heat or if the 30 sun should shine upon it, the heat must be transmitted through the insulating space before it can have any effect upon the candy or other material packed within the can.

The outer can 1 can be opened in any desired manner and in practice is preferably provided with the tongue 16 so that a strip will be torn from the can between the parallel lines 17, see Figure 1.

In so far as we are aware, we are the first 40 in the art to devise a practical manner of packing fudge so that it will be kept in substantially the same condition as when it is first packed for a considerable period of time.

45 In Figures 1, 2 and 3, we have shown the inner container as being formed from an integral piece of sheet material. It will be apparent that instead of making it out of one piece it can be made in sections as illustrated in Figure 5 or Figure 6. In Figure 5, the construction is the same as in Figure 3 except that a perforated sheet metal strip 18 has opposite edge portions constructed as at 19 so that when these are assembled in 50 the outer container the construction and function will be the same as that shown in Figures 1 to 3 inclusive. In some cases arising in practice it is not necessary to deflect the opposite edge portions as at 19 and 55 a rectilinear perforated sheet 20 as shown in Figure 6 may be employed to form the article container when a plurality of these are assembled within the outer container.

60 We have preferred to illustrate the outer container as having a polygonally shaped

contour in transverse section but it will be apparent that a circular or other shape may be employed so long as an insulating space is provided between the inner perforated container and the outer container. It will 70 of course be apparent that one of the end spacing members can be formed integral with or united with a section of the inner container or a wall of the inner container as may seem desirable in practice.

75 In will now be apparent that we have devised a novel and useful construction of a candy package which embodies the features of advantage enumerated as desirable in the statement of the invention and the above description, and while we have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described our invention, 90 what we claim as new and desire to secure by Letters Patent, is:

1. An article package, comprising an outer container, having sealed ends and a vacuum 95 therein, an inner article container formed from a single sheet of metal deflected to provide a plurality of corner centering members, adapted to contact with the inner surface of the outer container wall to form air insulating spaces around the inner article container, the walls of said inner article container having perforations therein, and upper and lower perforated end members positioned at the top and bottom of said outer container and having respectively upwardly and downwardly projecting flanges, thereby spacing the open ends of the inner article container from the outer ends of the outer container, thereby forming end insulating chambers isolated from the 100 annular air insulating spaces.

110 2. A container of the character stated, comprising an outer casing having sealed ends, and a vacuum therein, an inner polygonal rigid casing, the corners of which are extended to form lateral spacing projections which abut against the inner surface of the wall of the outer casing to center said inner polygonal casing, there being a vacuum chamber around said inner polygonal casing, 115 perforated top and bottom end plates arranged between each sealed end of said outer casing and the ends of said inner casing and abutting against the ends of said inner casing to form top and bottom vacuum chambers isolated from said annular vacuum chamber, and outer and central outwardly deflected flanges for said top and bottom end plates which abut against the sealed ends of 120 said outer casing.

3. A container of the character stated, comprising an outer casing having sealed ends, and a vacuum therein, an inner polygonal rigid casing, whose corners are extended to form upper and lower laterally opposed projections, which abut against the wall of the outer casing to center said inner polygonal casing, there being an annular vacuum chamber around said polygonal casing, perforated top and bottom end plates arranged between each sealed end of the outer casing and in abutting relation with said inner casing to form end vacuum cham-

bers isolated from said annular vacuum chamber, said inner casing having means of communication with both the annular and end vacuum chambers, and spacing devices for said top and bottom end plates, contacting with the top and bottom ends of said outer casing, said corner projections contacting with said top and bottom end plates. 15 20
